Kitesssu Nonstick Turkey Roasting Pan with Rack. Date First Available on Amazon.com Oct. 24, 2023. <https://www.amazon.com/dp/B0CG9NGWVN/ref> (Year: 2023).*Primary Examiner — Ricky Pham(74) *Attorney, Agent, or Firm* — Jose Cherson Weissbrot(57) **CLAIM**

The ornamental design for a roasting pan, as shown and described.

DESCRIPTION

FIG. 1 is a front, right, top perspective view of a roasting pan, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 1;

FIG. 11 is an enlarged view of detail 11 in FIG. 2;

FIG. 12 is an enlarged view of detail 12 in FIG. 3;

FIG. 13 is an enlarged view of detail 13 in FIG. 7;

FIG. 14 is a sectional view of 14-14 along the line in FIG. 7;

FIG. 15 is a sectional view of 15-15 along the line in FIG. 8;

FIG. 16 is an enlarged view of detail 16 in FIG. 14; and,

FIG. 17 is an enlarged view of detail 17 in FIG. 15.

(Continued)

The dash-dot-dash broken lines are for notating enlarged views and form no part of the claimed design.

1 Claim, 14 Drawing Sheets
